(57) **CLAIM**

The ornamental design for an electrical connector, as shown and described.

DESCRIPTION

FIG. 1 is a top perspective view of an electrical connector showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top elevation view thereof;

FIG. 7 is a bottom elevation view thereof; and,

FIG. 8 is a bottom perspective view thereof.

The broken line in the figure drawing views is included for the purpose of illustrating unclaimed environment only and forms no part of the claim designed.

1 Claim, 5 Drawing Sheets
